(57) CLAIM

The ornamental design for a mandible mask, as shown and described.

DESCRIPTION

A portion of the disclosure of this patent document contains material which is subject to copyright protection. The copyright owner has no objection to the facsimile reproduction by any-one of the patent document or the patent disclosure, as it appears in the Patent and Trademark Office patent file or records, but reserves all copyright rights whatsoever.

FIG. 1 is a perspective view of a mandible mask showing my new design;

FIG. 2 is a top view thereof;

FIG. 3 is a left side view thereof;

FIG. 4 is a front view thereof; and,

FIG. 5 is a right side view thereof; and,

FIG. 6 is a bottom view thereof.

The claimed design is shown in the drawings and no portions are disclaimed.
